US0D1054992S

(12) **United States Design Patent** (10) Patent No.: **US D1,054,992 S**
(45) Date of Patent: ** Dec. 24, 2024

(54) **CONNECTOR**

(71) Applicant: **Molex, LLC**, Lisle, IL (US)

(72) Inventors: **KrishnaPrasad Darbal Somanath**, Bangalore (IN); **Gautam Sharma**, Patna (IN); **Harsha Thyagaraj**, Bangalore (IN); **Sreenath A**, Kerala (IN); **Shivasharan Basavaraj Mahajanshetty**, Bangalore (IN)

(73) Assignee: **Molex, LLC**, Lisle, IL (US)

(**) Term: **15 Years**

(21) Appl. No.: **29/891,427**

(22) Filed: **May 5, 2023**

(51) LOC (14) Cl. **13-03**

(52) U.S. Cl.

USPC **D13/133**

CLAIM

The ornamental design for a connector as shown and described.

DESCRIPTION

FIG. 1 is a front top perspective view of a connector showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the remainder of the connector form no part of the claimed design.

1 Claim, 7 Drawing Sheets
